US0D1055669S

(12) **United States Design Patent** (10) **Patent No.:** **US D1,055,669 S**
(45) **Date of Patent:** **** Dec. 31, 2024**

(54) **MOUNT**

(71) Applicant: **SCAN2CAD INC.**, St Petersburg, FL (US)

(72) Inventor: **Hechuan Xu**, Shanghai (CN)

(73) Assignee: **SCAN2CAD INC.**, St Petersburg, FL (US)

(**) Term: **15 Years**

(21) Appl. No.: **29/950,840**

(22) Filed: **Jul. 5, 2024**

(30) **Foreign Application Priority Data**

May 29, 2024 (CN) 202430322269.6

(51) **LOC (14) Cl.** **08-08**

(52) **U.S. Cl.**

USPC **D8/349**; D14/238

(58) **Field of Classification Search**

USPC D14/230, 231, 238, 238.1; D8/354, 353,

D8/349, 363, 380, 381

CPC H01Q 7/00; H01Q 13/10; H01Q 9/285;

(57) **CLAIM**

The ornamental design for a mount as shown and described.

DESCRIPTION

FIG. 1 is a front and top perspective view of a mount according to our new design;

FIG. 2 is a front and bottom perspective view thereof;

FIG. 3 is a rear perspective view thereof;

FIG. 4 is a front view thereof;

FIG. 5 is a rear view thereof;

FIG. 6 is a left sideview thereof;

FIG. 7 is a right sideview thereof;

FIG. 8 is a top view thereof; and,

FIG. 9 is a bottom view thereof.

The broken lines illustrate portions of the mount that form no part of the claimed design.

1 Claim, 9 Drawing Sheets
